UNITED STATES PATENT OFFICE.

HENRI SCHLOESING AND BENJAMIN DÉGREMONT, OF MARSEILLES, FRANCE.

COIN-OPERATED LIQUID-VENDING APPARATUS.

SPECIFICATION forming part of Letters Patent No. 412,126, dated October 1, 1889.

Application filed June 11, 1889. Serial No. 313,891. (No model.) Patented in France July 3, 1888, No. 191,574.

To all whom it may concern:

Be it known that we, HENRI SCHLOESING and BENJAMIN DÉGREMONT, citizens of France, residing at Marseilles, France, have invented 5 certain new and useful Improvements in Coin-Operated Liquid-Vending Apparatus, (for which we obtained Letters Patent in France, No. 191,574, dated July 3, 1888;) and we do hereby declare the following to be a full, clear, and 10 exact description of the invention, such as will enable others skilled in the art to which it appertains to make and use the same, reference being had to the accompanying drawings, and to letters or figures of reference 15 marked thereon, which form a part of this specification.

The apparatus the subject of the present invention effects the automatic distribution 20 of liquids to the public on the simple deposit in the apparatus of coins of predetermined type. The exterior casing of this apparatus may be made of metal, wood, or of other substance, and it may be cylindrical or of prism form or quadrangular or other shape. We 25 will take for the present description an apparatus in wood and in form a quadrangular prism.

This apparatus is shown in the annexed drawings.

30 Figure 1 is an elevation of the interior of the apparatus shown with the side of the casing removed. Fig. 2 shows the front of the apparatus accessible to the public. Fig. 3 is a section on the line X X of Fig. 1. Fig. 4 is a partial elevation of the interior mechanism. Figs. 5, 6, 7, and 8 are detail views on a larger scale. Fig. 5 is a vertical section showing the 35 valve and float and other parts. Fig. 6 is a plan of the coin-receiver; Fig. 7, an elevation 40 of the same. Fig. 8 is a plan of the incline leading from the coin-slit to the receiver, also the space for the passage of the coin. Fig. 9 is an elevation, partly in section, of the interior of the apparatus as arranged to be worked 45 by a current of water. Fig. 10 is an elevation of the apparatus otherwise arranged.

The liquids which this apparatus may be used to distribute may be of various sorts.

A is an upper cistern suitably lined to contain the liquid. It can, however, be replaced 50 at will by a cask, as shown in Fig. 9. At the bottom of the interior an outflow-pipe B is

fixed, containing a valve arranged preferably as shown in Fig. 5.

Under the mouth of the outflow-pipe B a 55 tinned metal box C is placed, mounted on trunnions E E, and preferably of the triangular form shown. This receives the liquid flowing away by the pipe B. This box, which we call the "tipper" or "oscillatory delivery-vessel," delivers the liquid into a trough J, ending in a delivery-pipe K, leading to the glass placed outside for the consumer. The oscillations of the tipper or oscillatory delivery-vessel C are regulated and determined 60 as follows: In the tipper or oscillatory delivery-vessel C a float D is placed, which actuates the valve of the pipe B. The details of it are shown in Fig. 5. d is a rod, with a screw-thread upon it to raise and 70 lower the float. d' is a caoutchouc washer, forming the face of the valve. d² is a screw-nut on the rod d, and d³ is another nut. This arrangement permits the action of the float on the valve to be regulated. When the 75 tipper or oscillatory delivery-vessel has received the predetermined quantity of liquid, the float lifts the valve and stops the flow. By working the upper nut in one or the other direction, which lengthens or shortens the 80 travel of the float, the quantity of the liquid furnished to the consumer is regulated. When the tipper or oscillatory delivery-vessel C is ready for use, the consumer places a suitable coin in the slit I, which is exactly of the size 85 required to permit of its passage. The coin passes into the guide S and falls through a hole in it into a receiver G at the end of a lever F, fixed upon one of the trunnions of the tipper or oscillatory delivery-vessel C. The 90 weight of the coin tilts the tipper, which then pours its contents into the trough J, leading to the glass. The coin-receiver G comes against a stop L, and drops its coin to the bottom of the box. The coin-receiver G being thus lightened, a counterbalance-weight H, placed on the opposite side of the tipper, raises the tipper or oscillatory delivery-vessel and the coin-receiver, and this latter returns to its place beneath the guide S. The 100 tipper or oscillatory delivery-vessel, in consequence of the opening of the valve caused by the fall of the float, is then recharged with a fresh quantity of liquid. All this is quickly

carried out, the counterbalance-weight H being calculated to produce its effect on the fall of the coin. The upper cistern may have a double casing. In this case the space between the two casings may contain ice.

N is a cock to draw water from the reservoir M. With this water the customer may rinse his glass before using it. A basin placed under the mouth receives the waste and leads it to a drain.

In order that the consumer may not be exposed to the risk of putting in his coin at a moment when the apparatus is not in a state to work, the float D is attached by a chain to the end of an oscillating lever Q, rocking on a pivot on the frame. This lever carries at its other end a plate R, sliding in a groove placed at the back of the slit I. The plate, when at the lowest point of its travel, leaves the slit open in communication with the incline S. When the liquid is poured out of the tipper or oscillatory delivery-vessel, it lets the float fall, and this latter, drawing with it the end of the lever Q, pulls up the plate R, so as to cover the slit I, and prevents the introduction of the coin. As soon as the tipper or oscillatory delivery-vessel and the hopper have reascended, the filling of the tipper or oscillatory delivery-vessel, lifting up the float, causes the plate R to fall and leaves the slit I free. When the plate R does not fall, the slit I is permanently stopped, and so the public is informed that the apparatus is empty.

To protect the apparatus against fraud by the introduction of objects other than the predetermined coin, we construct the incline S and the coin-receiver G in the way shown in Figs. 6, 7, and 8. As seen, the incline is pierced with a hole just allowing the coin to pass, which thus falls into the receiver placed underneath. Any longer object which has passed the entrance-slit I will not fall into the hopper, but will pass over it and fall to the bottom of the box without affecting the tipper or oscillatory delivery-vessel. On the other hand, (the hole leaving a space in front of the coin-receiver,) small objects introduced into the slit and passing down the guide will fall through before reaching the coin-receiver. Coins which are too small, if they pass on to the coin-receiver, are not retained, and whatever their weight they will be without effect upon it, for the coin-receiver has two teeth to retain the coin of the proper size. These teeth end in points, which guide the receiver to its required position under the guide.

Fig. 9 shows a modification adapted to cases where it is better not to allow the liquid to remain in the tipper or oscillatory delivery-vessel. It is suitable in places which are well supplied with water and which are out of the reach of frost. Here the tipper or oscillatory delivery-vessel is not filled with the liquid to be vended, but with water, and the liquid flows directly from the pipe B into the overflow-pipe K, leading to the glass. The flow

is caused by the opening of the valve resulting from the fall of the float. This fall follows from the pouring out of the water contained in the tipper or oscillatory delivery-vessel. The tilting of this latter is caused by the lowering of the coin-receiver, as in the arrangement before described. The tipper or delivery-vessel rises, is filled with a predetermined quantity of water from a tank, and the float is elevated, which closes the valve. The flow is thus stopped and the apparatus made ready for fresh use. In this arrangement the mechanism is the same as before, excepting the introduction of the outlet-pipe J' and the different connection of the trough J, which no longer communicates with K, but with the water-delivery spout N. For the supply of water we add a pipe T, entering at the top of the cistern O.

O' is an overflow-pipe, and O² another pipe leading the water to the tipper C. The pipe O² is provided with a cock O³ to regulate the flow. The pipe O' leads the overflow-water to the trough J, into which the tipper or oscillatory delivery-vessel C empties. The trough J discharges itself on the outside by the pipe J'. The tipper or oscillatory delivery-vessel in this case has a small spout at the front, by which the overflow-water flows into the trough J when a consumer is not at hand.

The arrangement heretofore described for closing the coin-slot and notifying the public that the apparatus is not in condition for use is not applicable to the modified form of the apparatus just described, and illustrated in Fig. 9. We have therefore devised the following mechanism to be used in connection with the apparatus constructed as indicated in Fig. 9, in which the liquid to be vended is supplied from the cask or tank by a separate pipe directly to the consumer and the tipper or delivery vessel operated by water. A cylindrical box Y is screwed at Z onto the pipe B. A float U, provided with a rod, works in the interior of this cylinder. The float-rod presses against a lever carrying a plate, which serves to stop up the coin-slit. The length of this rod and the travel of the float are calculated, so that when the float U is raised—that is to say, when the liquid fills the cylinder Y—the lever remains free; but when the float U is at the bottom of its travel—that is to say, when the liquid has all been used—the rod comes against the lever and the plate is lifted and closes the slit.

Fig. 10 shows another modification. It has the advantage of being very simple and of easy construction. According to this arrangement the working of the tipper or oscillatory delivery-vessel and of the coin-receiver is as before; but the liquid is contained in a glass vessel, which generally has the form of a cask. It is provided at its upper end with an aperture n, which can be hermetically closed by means of a caoutchouc stopper. The outlet-pipe and the valve be-

fore described are replaced by a caoutchouc stopper traversed by two glass tubes *a* and *b*. The tube *a* serves to lead the liquid from the receiver to the tipper or oscillatory delivery-vessel. It is provided with a cock *m*. The tube *b*, tapered at the top, rises in the interior of the glass receiver to just above the surface of the liquid. It serves to admit air into this receiver. At its lower end it is provided with a sliding or telescopic tube *b'*, serving to regulate the height of the lower orifice.

This apparatus works in the following manner: The liquid to be distributed is poured into the receiver through the aperture *n*, after having closed the cock *m*. Then the aperture *n* is carefully closed by means of a caoutchouc cork, so as to avoid any entrance of air. The cock *m* may then be opened. The liquid runs directly into the tipper or oscillatory delivery-vessel by the tube *a*; but when the level of the liquid in the tipper reaches the mouth of the tube *b* air can no longer enter and the flow of the liquid is stopped. If at this moment a coin of predetermined size be dropped in the slit, it will tilt the tipper or oscillatory delivery-vessel, as has been before explained, and the tipper will be emptied. Afterward it returns to its original position; but the mouth of the tube *b*, being uncovered, will give passage to the air, which, entering the upper part of the receiver, will allow a fresh flow of liquid into the tipper or oscillatory delivery-vessel until its level has again reached the mouth of the tube *b*. The apparatus will then be ready to work a second time. The quantity of liquid to be given to the consumer is regulated by lowering or raising the sliding or telescopic tube *b'* at the end of the tube *b*. In this arrangement, the float no longer operating, the valve has no use except that of moving the plate which shuts and opens the coin-slit. It may be much smaller than in the preceding arrangements.

Of course we do not strictly limit ourselves to the described arrangements, which admit of many modifications in their details. Other accessory arrangements, such as movable pictures showing the actual interior conditions of the apparatus at any moment, may be usefully added; but of this it is unnecessary to speak.

Having now particularly described and ascertained the nature of our said invention and in what manner the same is to be performed, we declare that what we claim is—

1. In a coin-controlled liquid-vending apparatus, the combination of an oscillatory delivery-vessel or tipper pivotally supported at an intermediate point of its length, a valved supply-pipe for delivering liquid directly to said vessel or tipper, a vertically movable float located within said vessel or tipper, and connected by intermediate devices with the valve to regulate the quantity of liquid supplied to the vessel or tipper, and a coin-operated lever carried by said os-

cillatory vessel or tipper to tilt the latter and cause it to discharge its contents upon the introduction of a coin of proper denomination to said coin-lever, substantially as described.

2. In a coin-controlled liquid-vending apparatus, the combination of an oscillatory delivery-vessel or tipper pivotally supported at an intermediate point of its length, and having means for counterbalancing the same, a stationary trough arranged to receive the contents of the vessel, mechanism, substantially as described, for automatically refilling the vessel with a predetermined quantity of liquid after the vessel has been tilted to discharge its contents, and a coin-operated lever rigidly secured to said vessel to tilt the latter, substantially as and for the purpose described.

3. In a coin-controlled liquid-vending apparatus, the combination of an oscillatory counterbalanced delivery-vessel or tipper, a coin-operated lever connected to said vessel to tilt the latter, a fixed coinway intermediate the coin-slot and lever to guide the coin to the lever, a float operating in said delivery-vessel, a lever connected at one end to the float and carrying a coin-detaining plate at its opposite end, which plate is adapted to close the coin-slot when the supply of liquid is exhausted, and mechanism, substantially as described, for automatically refilling said vessel with a predetermined quantity of liquid, substantially as and for the purpose described.

4. In a coin-controlled liquid-vending apparatus, the combination of an oscillatory delivery-vessel or tipper, a supply-pipe leading from a suitable tank or reservoir and having an automatic valve, and a float operating in said vessel and connected to the valve to normally close the same and automatically open it when the vessel is emptied of its contents, arranged and combined for service substantially as herein shown and described.

5. In a coin-controlled liquid-vending apparatus, the combination of an oscillatory delivery-vessel or tipper, a supply-pipe having an automatic valve, a float operating in said vessel and connected to the valve to control the latter, and a coin-operated lever connected to said vessel to tilt the latter, substantially as and for the purpose described.

6. In a coin-controlled liquid-vending apparatus, the combination of an oscillatory counterbalanced delivery-vessel or tipper, a supply-pipe having an automatic valve, a float operating in said vessel and connected to the valve, a coin-operated lever fixed to the vessel, and a coinway beneath which the free end of said lever is normally arranged to receive the coin directly therefrom, substantially as and for the purpose described.

7. A fixed inclined coinway having a coin-slot of the proper diameter formed therein, and a lever carried by a tiltable vessel or re-

ceptacle and normally held by the latter in position beneath the coinway to receive a coin after it passes through the slot in said coinway, for the purpose described.

5 8. A fixed inclined coinway having a coin-slot, a tiltable receptacle, and a lever carried by said receptacle and having a coin-holder at its free end, said coin-holder being provided with vertical prongs *g*, for the purpose 10 described, substantially as set forth.

9. In a coin-operated liquid-vending apparatus, the combination of an oscillatory delivery-vessel or tipper, a fixed supply-pipe leading from a suitable tank and having a 15 valve-seat, a float operating in said vessel, and an endwise-movable valve-stem connected to said float and having a valve fitted in the supply-pipe, for the purpose described, substantially as set forth.

10. In a coin-operated liquid-vending apparatus, the combination of an oscillatory vessel or tipper, a supply-pipe leading from a suitable reservoir or tank and having an automatic valve, a float operating in said vessel and connected to the valve, a water-chamber arranged to deliver a predetermined quan- 25

30 tity to said vessel, and a water-supply pipe leading to the water-chamber, substantially as and for the purpose described.

11. In a coin-operated liquid-vending apparatus, the combination of an oscillatory vessel or tipper, a water-chamber having an independent supply-pipe and arranged to deliver its contents to said vessel, a supply-pipe leading from a beverage-tank and having an 35 automatic valve, a float operating in the vessel and connected to said valve, a lever controlled by the float and having a coin-detaining plate at one end, an elevated chamber intermediate the beverage-tank and its supply-pipe, and a float in said chamber having a 40 rod which connects with the lever, all arranged and combined for service substantially as described, for the purpose set forth.

In testimony whereof we affix our signatures in presence of two witnesses.
